UNITED STATES PATENT OFFICE.

CLARENCE D. SHAEFFER, OF HUTCHINSON, MINNESOTA.

MAP HOLDER.

Application filed May 21, 1928. Serial No. 279,360.

This invention relates to map and chart holders and particularly to map and chart holders which may be used on vehicles or in other exposed places.

5 It is the object of the invention to provide a novel and improved map holder which will incase a comparatively long flexible map or chart and which will include means for exposing different portions of the map to 10 view from time to time, which can be readily manipulated.

To this end, the invention consists in the novel parts and novel combinations of parts, hereinafter defined in the claims and described in the following specification, made 15 in connection with the accompanying drawings, wherein like reference characters refer to the same or similar parts throughout the various views and, in which,

20 Fig. 1 is a perspective view of the forward inside portion of an automobile illustrating one of the map holders of the present invention applied thereto;

Fig. 2 is an enlarged plan view of the map holder, certain of the parts being broken away and shown in section;

Fig. 3 is a view in side elevation of the holder on an enlarged scale, certain of the parts being broken away and shown in section;

Fig. 4 is a transverse section of the device taken on the line 4-4 of Fig. 2, as is indicated by the arrows;

Fig. 5 is a horizontal section taken on the line 5-5 of Fig. 4, as is indicated by the arrows, and

Fig. 6 is a perspective view of one end of the map holder with the cover removed.

Referring to the drawings, a long rectangular open-topped casing A is provided, which includes the bottom 7, sides 8, and ends 9. The ends 9 terminate short of the tops of the sides 8 and the said sides 8 have inwardly extending grooves 10 formed at 40 their upper edges which project above the level of the ends 9. The grooves 10 are preferably formed by first bending the upper edges of the sides 8 straight inwardly throughout their lengths to form inwardly 45 extending flanges 11. The innermost edges of these flanges are then reversely bent and U-shaped to form the grooves 10 with one side of the grooves abutting the lower sides of the flanges 11, and the outer sides of the 50 grooves abutting the main portions of the sides 8. The flanges 11, inwardly short dis-

tances from the ends thereof, are cut off at 13 so that the grooves 10 will terminate short of the ends of the casing.

Extending below the ends of the grooves 60 10 transversely of the casing are partitions 14. These partitions, adjacent either end thereof, have downwardly and outwardly extending notches 15 formed therein which notches flare outwardly towards the top 65 edges of the partitions. Joining the notches 15, and extending downwardly therefrom toward the bottom 7 of the casing, are the circular notches 16 which form bearings for two roller shafts 17 and 18. The said shafts 70 extend longitudinally of the casing and one of the shafts, such as shaft 18, projects through a slot 19 running downwardly from the upper edge of one of the ends 9 and extends outwardly from one end of the casing 75 for some little distance, and is provided at its outer end with a knob 20 for turning the shaft. The other ends of the shafts 17 and 18 preferably terminate just short of the inner sides of the ends 9 of the casing. 80 Mounted on both ends of each of the shafts 17 and 18, between the partitions 14 and the ends 9 of the casing, are small drums 21, and resilient endless belts 22 preferably composed from rubber, or similar material, extend 85 between and over the two drums 21 adjacent the two ends of the casing. The shafts 17 and 18 are preferably provided with slots 23 adjacent their central portions for reception of the outwardly and centrally flaring 90 ends of a long flexible member 24. Member 24 may be a map, chart or similar device. The ends of the map will be removably secured in the grooves 23 of the two shafts and one end of the map will be rolled on one of 95 the shafts 17 and the other end of the map will be rolled on the other shaft 18, so that a portion of the map will extend between the two shafts adjacent the top of the casing. A suitable cover 25 comprising a rectangular 100 frame, having a glass or similar transparent material mounted therein, is slidably securable within the grooves 10 to close the upper side of the casing and yet permit the map or chart to be viewed from the outer side of 105 the casing. A U-shaped bracket 26 is secured to the lower side of the bottom 7 adjacent the center thereof, to extend longitudinally of the casing, while a similar U-shaped bracket 27 is secured to the lower side 110 of the bottom 7 adjacent one end thereof, to extend transversely of the casing. A suit-

able arm 28 is provided which may be secured as by screws to a suitable support, such as the support 29, and the casing may be secured to the arm 27 to extend either 5 vertically or horizontally in respect thereto.

Considering the map holder to be in assembled condition with a flexible map wound on the rollers 17 and 18, a bracket of the map holder may be mounted in an automobile in the position illustrated in Fig. 1, if desired. The driver of the automobile can readily refer to the map as he steers his course along a highway, and the casing provided for the map will prevent the same 10 from being torn or blown by the wind and from becoming soiled by usage and by dust of the road. When the driver desires to turn the map to expose a different section thereof, he simply turns the knob 20, where- 15 upon the two resilient belts 22 will cause both shafts to revolve in the same direction, thereby permitting a portion of the map to be unwound from one shaft and a portion of the map to be wound upon the other shaft. 20 Due to the fact that the belts 22 are resilient, sufficient friction will be applied to the drums 21 on the two shafts, to hold the shafts in the position to which they have been turned. There will thus be no tendency 25 for the exposed portion of the map to become slack and the same will be tightly stretched at all times between the two shafts. The circular bearing notches 16, which adjoin the flaring notches 15 in the partitions 14, 30 will prevent the shafts 17 and 18 from slipping upwardly, due to the fact that shoulders will be formed at the point of juncture between the notches 15 and 16. The shafts, accordingly, will be securely held in place 35 when in use. When it becomes desirable to replace the map in use in the map holder by another map, the cover 25 may be withdrawn from the grooves 10 to expose the upper portion of the holder. The shafts 17 40 may then be raised directly upwardly from the bearing notches 16, whereupon the shaft may be removed from the partitions 14 by pulling the same inwardly and upwardly through the notches 15. Due to the fact 45 that the grooves 10 terminate at 13 inwardly from the ends 9 of the casing, the drums 21 will not strike any portion of the casing as the shaft 17 is removed. Prior to the removal of the shaft 17, the map 24 will preferably be wound entirely upon the shaft 17. 50 A second shaft 17 carrying a different map 24 may then be substituted for the original shaft 17 and map carried thereby, or the original map 24 may be removed from the original shaft 17 and another map of the same type applied thereto, by winding the same on the shaft. When the new shaft 17, 55 together with the map carried thereon, or the old shaft, having a new map secured thereto, is again inserted within the casing so

that the shaft rests in the bearing notches 16, the unsecured end of the map 24 will be extended from the shaft 17 and will be inserted within the groove 23 on the shaft 18, whereupon by rotation of the shaft 18, one 70 end of the map may be wound thereon. The cover 24 may then be applied to the casing, whereupon the same is again ready for use. It will be apparent that the shaft 18 can also be removed from the casing, if desired. 75

The device is simple in construction and in operation, comprises few parts and is inexpensive to produce. It is found particularly useful when applied to automobiles for carrying State maps. When the map 80 holder is used in connection with maps having their greatest dimension running from north to south, the map holder will be applied to the supporting arm 28 in the manner illustrated in Fig. 1, so that the map holder 85 extends substantially vertically. When the map holder is used in connection with maps which have their greatest dimensions running east and west, the casing will be secured to the arm 28 by slipping the arm in the bracket 26, whereupon the map holder will be disposed substantially horizontally. The inventor has successfully demonstrated the device in actual practice.

It will, of course, be understood that various changes may be made in the form, details, arrangement and proportions of the various parts without departing from the scope of the present invention. 95

What is claimed is:

1. A map holder comprising an open topped casing, a pair of partitions disposed transversely of the casing adjacent the ends thereof, said partitions having notches formed therein adjacent their ends, said notches extending diagonally downwardly and toward the sides of said casing from the tops of said partitions and said partitions having bearing portions communicating with said notches and extending downwardly toward the bottom of said casing from said notches, and roller shafts journaled in said bearing portions whereby said shafts can be rotated and said shafts may be raised upwardly from their bearing portions into the notched portions of said partitions to remove the same. 100

2. A map holder comprising an open topped rectangular casing, the upper inner edges of the sides of said casing having 105 grooves formed therein at a higher level than the ends of said casing, the upper edges of said sides terminating short of the ends of the casing, partitions disposed transversely in the casing adjacent the ends thereof and between the ends of said grooves, said partitions having notched portions adjacent either end projecting downwardly and toward the sides of said casing and said partitions having notched bearing portions join- 110 115 120 125 130

ing said first mentioned notched portions and extending straight downwardly from said first mentioned notched portions, rollers journaled in said notched bearing portions of said partitions, and a cover adapted to be slidably mounted in the grooves of said sides to close the top of said casing whereby

when said cover is removed, said shafts can be removed without interference from the grooved portions of the sides of the said 10 casing.

In testimony whereof I affix my signature.

CLARENCE D. SHAEFFER.
